UPHOLSTERY SPRING EDGE CONSTRUCTION

Filed April 12, 1944

UNITED STATES PATENT OFFICE

2,439,789

UPHOLSTERY SPRING EDGE
CONSTRUCTION

Albert M. Bank, Jersey City, N. J.

Application April 12, 1944, Serial No. 530,609

10 Claims. (Cl. 155—179)

1

This invention relates to upholstery spring edge construction. It is particularly directed to spring seats employing zig-zag springs and spring edge therefor.

An object of this invention is to provide a spring edge construction of the character described comprising a cantilever spring mounted on each zig-zag spring and so constructed and engaged with the zig-zag spring as to prevent side swing or movement of the cantilever spring in either direction.

Another object of this invention is to provide in a spring edge construction of the character described, a cantilever spring made of spring wire and having a long arm and a short arm interconnected at their forward ends, both arms being so woven into its supporting zig-zag spring, as to firmly anchor the cantilever spring to the zig-zag spring.

Zig-zag springs such as are used in spring seats, are made of various gauge wire. Furthermore, the number of turns per unit length of said springs often vary. It is advantageous to make the cantilever springs of uniform length irrespective of the gauge of the zig-zag spring or the number of turns of said zig-zag spring. Furthermore, the forward edges of the cantilever springs should always be at a predetermined position above the front portion of the frame of the spring seat. In accordance with the present invention, applicant's cantilever springs are so constructed that the rear ends of the arms thereof are adjustable relative to the zig-zag spring to allow for variations in the gauge of the wire or numbers of turns.

Yet another object of this invention is to provide a cantilever spring of the character described having a long arm and a short arm and so constructed that as pressure is imposed thereon, resistance to such pressure builds up, whereby to provide a spring edge which will increase the comfort to the person sitting on the seat.

Yet a further object of this invention is to provide a strong, durable and compact spring seat construction which will be relatively inexpensive to manufacture, easy to assemble, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

2

In the accompanying drawings in which is shown one of the various possible illustrative embodiments of this invention.

Fig. 1 is an elevational cross-sectional view of a spring seat embodying the invention; Fig. 2 is a top plan view thereof; Fig. 3 is a partial front view thereof; and Fig. 4 is a perspective view of a cantilever spring embodying the invention and mounted on a zig-zag spring.

Referring now in detail to the drawing, 10 designates an upholstery seat construction provided with a spring edge and embodying the invention. The same comprises a seat frame 11 having side walls 12, a front wall 13, and a rear wall 14. Mounted on the frame 11 are a plurality of arched parallel zig-zag springs 15. The front ends of the spring 15 are connected to the upper edge of frame portion 13 by brackets 16. The rear ends 20 of the spring 16 are mounted on the upper ends of frame wall 14 by means of brackets 17. Each zig-zag spring 15 comprises parallel arms, rungs or portions 18 interconnected by loops or turns 19.

Mounted on each zig-zag spring 15 is a cantilever spring 40, the latter being interconnected by an edging wire 60 thus forming a spring edge for the seat. Each spring 40 is made of spring wire and comprises a long arm 42 and a short arm 43 interconnected at the front by a wire portion 44. The cantilever spring is mounted on spring 15 by weaving arms 42, 43 within the turns of spring 15 as shown in the drawing.

Arms 42 and 43 have parallel similar portions 45 and 46 disposed in the same plane with spring portion 44. The short arm 43 also has a portion 47 extending from portion 46 and connected thereto by a bend 48. Portion 47 is inclined downwardly and passes through spring 15 engaging within a loop 19 on one side of said spring. Thus 40 portion 47 passes from above spring 15 to below said spring. Extending from portion 47 is a portion 49 connected to portion 47 by a bend 50. Portion 49 passes beneath spring 15 and at the end thereof is an upwardly and outwardly extending curved hook or eye terminal portion 51 which passes upwardly through the spring within the next loop 19 on the same side and around said loop. Thus the short arm passes beneath two adjacent arms or rungs 18 of spring 15 and 50 engages two adjacent loops 19 on opposite sides of said arms.

The long arm 42 has a portion 55 extending from portion 45 and connected thereto by a bend 56. Portion 55 passes above the arm 18, beneath 55 which portion 47 of the short arm 43 passes.

Extending from portion 55 of the long arm 42 is a portion 57 connected to portion 55 by a bend 58. Portion 57 passes beneath the arm 18 beneath which portion 49 of the short arm passes. Said portion 57, it will be noted, passes down through a loop 19 at the opposite side of spring 15 and interconnecting the two arms 18 beneath which the short arm engages. Said portion 57 also passes beneath the next arm 18 and at the end thereof is an upwardly and outwardly curved hook or eye terminal portion 59 engaging the next loop 19. Thus the long arm likewise engages beneath two arms 18 of spring 15, and engages with a pair of loops 19 at the side of the spring 15, opposite to the two loops which are engaged by the short arm. With such construction both arms are inside of a pair of loops and the cantilever spring 40 cannot swing to the right or to the left but is firmly anchored to the zig-zag spring.

It will be noted that the cantilever spring 40 may be shifted forwardly or rearwardly to a certain extent to permit adjustment for bringing portion 44 to a predetermined position, thus allowing for variations in the gauge of the spring 15 and for variations in the number of loops of which said spring is made.

As pressure is increased at the outer end of the cantilever springs, first the short arm presses down against an arm 18 of the spring 15 and then the long arm presses down on the next arm 18. The resistance to downward pressure thus builds up to add comfort to the seat. It will be noted that both the long and short arms engage beneath two arms of the zig-zag spring and over two turns or loops, thus making a good anchor.

The outer end portions 44 of spring 40 are interconnected by an edge wire 60 having a front portion 61 connected to said portions 44 by split clips 63. Extending from the ends of wire portion 61 are bent back arm portions 65 hooked onto intermediate portions of the outside zig-zag wires in any suitable manner.

It will thus be seen that is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In a spring seat, a frame, a zig-zag spring mounted on said frame and a cantilever spring mounted on the zig-zag spring, said cantilever spring extending above the zig-zag spring and having a short arm and a long arm interconnected at one end, the short arm having a portion engaging beneath a pair of adjacent arms of said zig-zag spring and portions passing through a pair of adjacent loops on one side of said zig-zag spring, and the long arm having a portion engaging beneath one of the first pair of arms and the next adjacent arm of said zig-zag spring, and portions passing through a pair of loops on the opposite side of said zig-zag spring and staggered with respect to the first-mentioned pair of loops the ends of said arms being secured to the loops through which they pass.

2. In upholstery spring construction, a frame, a zig-zag spring mounted thereon, and a cantilever

lever spring mounted on the zig-zag spring and extending over said zig-zag spring, and having a short arm and a long arm interconnected at one end, said short arm having a portion engaging beneath a pair of arms of the zig-zag spring and portions passing through a pair of loops on the opposite sides of said arms, and on one side of said zig-zag spring, a portion engaging over one of said loops and said long arm having a portion passing through a loop at the opposite side of said zig-zag spring and between the first-mentioned pair of loops, and said long arm engaging beneath a pair of arms of said zig-zag spring and having a portion engaging over the next loop on said opposite side of said spring.

3. In upholstery spring construction, a zig-zag spring comprising arms interconnected by turns, and a cantilever spring mounted thereon and extending thereover, said cantilever spring

20 being made of a single piece of wire and having arms interconnected at one end, one arm of said cantilever spring having portions passing through a pair of turns on one side of said zig-zag spring, and the other arm of said cantilever spring having portions passing through a pair of turns on the opposite side of said zig-zag spring, each arm of said cantilever spring having portions passing beneath and engaging a pair of arms of said zig-zag spring, one of the arms of said cantilever spring being longer than the other arm of said cantilever spring, the terminal portions of said arms engaging over turns of said zig-zag spring.

4. In combination, a zig-zag spring comprising arms interconnected by turns, and a cantilever spring mounted thereon and extending thereover, said cantilever spring comprising a pair of arms interconnected at one end, one of

40 said arms of said cantilever spring having a portion passing down through the zig-zag spring and within one of the turns thereof on one side thereof, and having a portion passing beneath and engaging a pair of arms of said zig-zag spring, and being provided with an upwardly and

45 outwardly curved hook terminal portion passing through and engaging over the next turn of said zig-zag spring on the same side, the other arm of said cantilever spring having a portion passing down through the zig-zag spring and within a turn of said zig-zag spring at the opposite side thereof and between said first-mentioned turns of said zig-zag spring, and said second arm of said cantilever spring having a portion passing beneath and engaging a pair of arms of said zig-zag

50 spring and provided with an upwardly and outwardly hooked terminal portion passing through and engaging over the next turn of said zig-zag spring on said opposite side.

5. In a spring seat, a frame, a zig-zag spring mounted on said frame and a cantilever spring mounted on the zig-zag spring and extending thereover, said cantilever spring having a short arm and a long arm interconnected at one end, the short arm having a portion engaging beneath a pair of arms of said zig-zag

60 spring and portions passing through a pair of loops on one side of said zig-zag spring, and the long arm having a portion engaging beneath a pair of arms of said zig-zag spring, and portions passing through a pair of loops on the opposite side of said zig-zag spring and staggered with respect to the first-mentioned pair of loops said arm having terminal portions engaging over the zig-zag spring.

6. In combination, a zig-zag spring comprising arms interconnected by turns, and a cantilever

spring mounted thereon and extending thereover, said cantilever spring comprising a pair of arms interconnected at one end, one of said arms of said cantilever spring having a portion passing down through the zig-zag spring and within one of the turns thereof on one side thereof, and having a portion passing beneath and engaging a pair of arms of said zig-zag spring, and being provided with a portion engaging over the next turn of said zig-zag spring on the same side, the other arm of said cantilever spring having a portion passing down through the zig-zag spring and within a turn of said zig-zag spring at the opposite side thereof and between said first-mentioned turns of said zig-zag spring, and said second arm of said cantilever spring having a portion passing beneath and engaging a pair of arms of said zig-zag spring and provided with a portion engaging over the next turn of said zig-zag spring on said opposite side.

7. In upholstery construction, a frame, zig-zag springs mounted on said frame, and cantilever springs mounted on the zig-zag springs and extending thereover, each zig-zag spring comprising arms interconnected by turns, each cantilever spring comprising a pair of arms interconnected at one end, each arm of the cantilever spring having a portion passing down through a turn of a zig-zag spring, and a portion engaging beneath a pair of arms of a zig-zag spring, and a portion passing upwardly through a turn of a zig-zag spring, and a portion engaging over a turn of said zig-zag spring.

8. In upholstery construction, a frame, zig-zag springs mounted on said frame, and cantilever springs mounted on the zig-zag springs and extending thereover, each zig-zag spring comprising arms interconnected by turns, each cantilever spring comprising a pair of arms interconnected at one end, each arm of the cantilever spring having a portion passing down through a turn of a zig-zag spring, and a portion engaging beneath a pair of arms of a zig-zag spring, and a portion passing upwardly through a turn of a zig-zag spring, and a portion engaging over a turn of said zig-zag spring, the last-mentioned portion of each arm comprising a downwardly opening terminal hook engaging said turn.

9. In upholstery construction, a frame, zig-zag springs mounted on said frame, and cantilever springs mounted on the zig-zag springs and extending thereover, each zig-zag spring comprising arms interconnected by turns, each cantilever spring comprising a pair of arms interconnected at one end, each arm of the cantilever spring having a portion passing down through a turn of a zig-zag spring, and a portion engaging beneath a pair of arms of a zig-zag spring, and a portion passing upwardly through a turn of a zig-zag

spring, and a portion engaging over a turn of said zig-zag spring, the last-mentioned portion of each arm comprising a downwardly opening terminal hook engaging said turn, one arm of each cantilever spring being located adjacent one side of a zig-zag spring, and the other arm of said cantilever spring being located adjacent an opposite side of a zig-zag spring.

10. In upholstery construction, a frame, zig-zag springs mounted on said frame, and cantilever springs mounted on the zig-zag springs and extending thereover, each zig-zag spring comprising arms interconnected by turns, each cantilever spring comprising a pair of arms interconnected at one end, each arm of the cantilever spring having a portion passing down through a turn of a zig-zag spring, and a portion engaging beneath a pair of arms of a zig-zag spring, and a portion passing upwardly through a turn of a zig-zag spring, and a portion engaging over a turn of said zig-zag spring, the last-mentioned portion of each arm comprising a downwardly opening terminal hook engaging said turn, one arm of each cantilever spring being located adjacent one side of a zig-zag spring, and the other arm of said cantilever spring being located adjacent an opposite side of a zig-zag spring, one arm being shorter than the other, and the arms of the zig-zag spring engaged by one arm of said cantilever spring being offset with respect to the arms of the zig-zag spring engaged by the other arm of said cantilever spring.
